UNITED STATES PATENT OFFICE.

RUTH GEORGE, OF OMAHA, NEBRASKA.

DESIGN FOR A COMBINATION DOLL AND PINCUSHION.

Application filed October 22, 1924. Serial No. 11,145. Term of patent 3½ years.

To all whom it may concern:

Be it known that I, RUTH GEORGE, a citizen of the United States, residing at Omaha, county of Douglas, State of Nebraska, have invented a new, original, and ornamental Design for a Combination Doll and Pincushion, of which the following is a specification, reference being had to the accompanying drawing, forming a part thereof.

In the drawing:

Figure 1 is a front elevation of the combination doll and pincushion.

Figure 2 is a side elevation of the combination doll and pincushion.

I claim:

The ornamental design for a combination doll and pincushion as shown.

RUTH GEORGE.
